CHAIR AND THE LIKE

Frank William Crossley-Holland, Dunstable,
EnglandApplication May 18, 1935, Serial No. 22,256
In Great Britain May 24, 1934

1 Claim. (Cl. 155—125)

This invention relates to chairs and the like and has for its object to provide chairs and the like designed on the basis of anatomical considerations to give the maximum of rest or repose to the body in a seated posture while permitting variation of the position within relatively wide limits.

In the seated posture, the thickness of the muscular tissue over the heads of the femurs is relatively small, being somewhere in the neighbourhood of one and a half inches; the average distance between the heads of the femurs in an adult person is in the neighbourhood of four to five inches.

It is desirable that, whatever position is assumed by the body while in a seated posture, the thrust of the weight of the body shall be taken vertically through the spine and the weight shall be so far as possible uniformly distributed so that the pressure upon the tissues covering the heads of the femurs shall be equalized.

It is, furthermore, desirable that the backward inclination of the body should be such as to give the maximum relaxation of the erector spinal muscles, while the height of the seat should be such that, with the feet on the ground, the pressure upon the thighs should be reduced.

According to the invention, the surface of the seat of the chair or the like is concave and conforms with the internal surface of a cylinder substantially two feet ten and a half inches in diameter and is defined by a chord of one foot ten inches, while the rearward inclination of the back rest relatively to the horizontal is 110° and, generally, the minimum height of the seat from the ground level is sixteen inches.

Normally the chair or the like will be provided with arm rests at a convenient height, for instance, a height of twenty-three and a half inches from the ground level so that the arms of the person using the seat rest upon the arm rests, while the heads of both of the femurs will be supported upon the seat, the line of the spine remaining straight. In other words, the line of the spine will be positioned radially with respect to the curvature of the seat.

Preferably, the back rest is somewhat hollow so as to provide points of support for instance for the spine and the ribs or shoulders on either side thereof.

Conveniently, in accordance with the invention, the arm rests are arranged to provide tables on either side of the seat and the width of the tables is advantageously such that without strain the

hand of the person using the chair can reach to the edge thereof.

Generally, in accordance with the invention, the table portions are substantially semicircular while the back rest may be suitably curved in an upward direction from the tables towards its centre.

The frame and/or under-frame of the chair may similarly be in the main formed of curved members.

Thus, for instance, there may be provided members functioning as legs extending downward and outward in a suitable curve, the members at the front being connected with the member at the back by stretchers, one on either side of the seat, and from each of these stretchers there may be arranged to extend from its mid point, preferably, in a curve, to substantially the level of the arm rests, a stay adapted to provide a support for the outer edge of the table portion.

Generally, the members functioning as legs will be connected with or be part of members forming the upper portion of the frame of the chair, in which case the front and rear portions of the frame will be generally of X-form, the limbs of the X being, however, suitably curved and between the upper and lower limbs of such portions there extend the upper portions of the legs to form stays terminating substantially at the level of the arm rests.

In the case of a chair for use in the open, the seat itself may be formed of staves, for instance the staves of a barrel, the face of each of which is somewhat concave.

While, generally, the main portion of the frame and the stays will be curved and the table portions be substantially half circular members, in certain cases the form and shape of these elements may be modified provided that the formation of the seat and the inclination of the back above defined is retained.

One construction of chair in accordance with the invention is illustrated by way of example in the accompanying drawing, in which:—

Figure 1 is a front view in elevation of the chair,

Figure 2 is a plan view, and

Figure 3 is a view in section on the line III—III of Figure 1.

In the construction illustrated the seat is formed of a plurality of staves 1, the upper surface of each of which is concave and the side edges suitably bevelled so that when assembled they will form a seat which is concave and conforms with the internal surface of a cylinder substantially two feet ten and a half inches

in diameter and is defined by a chord of one foot ten inches, the minimum height of the seat from the ground level being sixteen inches and with the seat there is associated a back rest 2 provided with a hollowed out portion 3 adapted to conform with the back of an average individual when at rest or relaxed so as to give a support to the spine and the bones on each side of the spine, for instance, the shoulder blades or the ribs at the back of the person.

This back portion is given a rearward inclination relatively to the horizontal of 110° and as will be seen from the drawing it is curved in an upward direction to its centre from the level of the arm rests 4 arranged at either side of the seat and constituting tables of substantially semi-circular form.

These arm rests may be arranged, as above stated, at a height of about twenty-three and a half inches from the ground level so that the arms of a person using the seat may rest upon them so that the heads of both of the femurs will be supported upon the seat, the line of the spine remaining straight, or positioned radially with respect to the curvature of the seat.

The members 5 functioning as legs are connected together by a frame 6 of X-form, the limbs of which are suitably curved and between the upper and lower limbs of such portions there extend the upper portions of the legs. With the stretchers 7 connecting the front legs with the rear legs are connected curved stays 8 extending upward substantially to the level of the table portions 4, a member 9 connecting the upper ends of these stays with side members 10.

In the construction illustrated it will be seen that the staves 1 are hollowed or arranged to

provide a surface inclining in an upward and forward direction to the front of the seat.

Having now described my invention, what I claim as new and desire to secure by Letters Patent is:—

A chair or the like comprising a seat, the surface of which is concave and conforms with the internal surface of a cylinder substantially two feet ten and a half inches in diameter and is defined by a chord of one foot ten inches, the axis of which extends in a horizontal direction from the back to the front of the seat, a back rest secured in fixed relation with the seat and inclined in a rearward direction at an inclination of 110° to the horizontal, and connected with the seat, arm rests at a height such that the arms of the person using the seat may bear upon the arm rests, with the heads of both of the femurs supported upon the seat and the line of the spine straight, each of said arm rests constituting a table, a frame in the form of an X arranged on its side and having curved limbs corresponding with the curvature of the seat secured to the front portion of the seat, and a further member of like form secured to the rear portion of the seat, legs extending outward in a curve from the seat and secured to the ends of the X-frames and providing adjacent to their upper ends supports for the inner edges of the arm rests and downward to provide portions adapted to bear upon the ground, a stretcher extending between the legs on each of the two sides of the seat, and a stay extending in a curve upward from each of said stretchers to support the outer edge of the arm rests.

FRANK WILLIAM CROSSLEY-HOLLAND.
